SEWING MACHINE

Norman V. Christensen, Chicago, Ill., assignor to
 Union Special Machine Company, Chicago, Ill.,
 a corporation of Illinois

Application January 13, 1945, Serial No. 572,595

9 Claims. (Cl. 112—256)

1

This invention relates to an improved sewing machine construction and more particularly to a machine of the type having a base with a vertically rising standard adjacent one end and an overhanging arm projecting from the standard and extending over the work supporting surface of the base.

An object of the invention has been to provide a machine of the above indicated character, which is of simple, sturdy and compact construction and which is thoroughly reliable in operation at high speeds. Toward these ends the machine is provided with a single rotary shaft which is journaled in the upper portion of the frame and extends from a point exterior of the vertical standard, adjacent its top, to a point within the needle head carried by the overhanging arm. This shaft is arranged to drive a reciprocable needle bar and also various instrumentalities in the base. These include one or more loopers of the 4-motion type and a feed dog of the 4-motion type.

A further object has been to provide a chain stitch sewing machine of the flat-bed type, and more especially a closely coupled machine having a short base and short overhanging arm, adapted to sew edge seams, the mechanism being capable of effecting the desired stitching at high speeds with minimum vibration and quiet operation.

An important feature of the invention is the provision of an improved looper construction with connections from the single rotary shaft, mentioned above, for imparting both loop-taking and shedding movements and needle avoid movements to the loopers.

Another feature of the invention is the provision of a hollow frame for housing the various operative devices of the machine and the provision of means for effecting automatic lubrication of these devices whenever the machine is in operation.

A specific improvement forming part of the present invention is the provision, in a flat bed machine having a simple frame construction of the type above indicated, of a single rocker member driven from the rotary shaft in the upper arm and connected with the feed dog and the loopers in the base to impart the feed stroke and looper avoid movements to these parts, respectively. A particular feature of this part of the construction is the provision for separate adjustment of the feed stroke and the looper avoid movement imparted upon the rocking of the single rocker member. Thus provision is made not only for varying the stitch length but also for adjusting the looper avoid movement to compensate for different thicknesses of loopers or needles.

2

Still another feature of the invention is the provision of means for increasing the permissible speed of operation of the machine by constantly removing heat from the interior of the frame and thereby maintaining the various operating devices at a relatively low temperature during operation of the machine. For this purpose the machine is equipped with an individual driving motor and clutch adapted not only to drive the sewing machine but to drive also a blower arranged to maintain a constant suction upon the space within the frame of the machine. Thus, as the machine is operated there is a continuous withdrawal of warm air and a continuous influx of cooler air. This is accomplished, moreover, in such a way as to reduce to a minimum the loss of lubricant in the air withdrawn from the frame.

Other objects, features, and advantages of the invention will appear from the detailed description of an illustrative form of the invention which will now be given in conjunction with the accompanying drawings in which:

Figure I is a view, partly in front elevation and partly in longitudinal vertical section through a combined sewing machine and driving unit therefor mounted on a table, shown only in part.

Figure II is an enlarged longitudinal vertical section through the sewing machine illustrated in Figure I.

Figure III is a further enlarged view in horizontal section through the base of the machine taken at substantially the elevation indicated by the line III—III in Figure II.

Figure IV is a similarly enlarged horizontal section through the base of the machine taken substantially along the plane indicated by the line IV—IV in Figure II.

Figure V is an enlarged vertical section through the base and standard of the machine, taken substantially along the broken line V—V in Figure I.

Figure VI is a view, partly in end elevation and partly in vertical section, taken substantially along the broken line VI—VI of Figure I, the end cover plate of the needle head being removed to disclose the parts within said head.

Figure VII is an enlarged detail view in vertical section through one of the splash plates and is taken along the line VII—VII of Figure V; and

Figure VIII is a detail view in transverse section showing a modified form of feed bar and associated wall opening which may be employed.

Referring now to the drawings and more particularly to Figure I, the improved construction embodying the present invention has been illustrated as applied to a sewing machine, designated generally by the reference numeral 10,

mounted on a table top 11 forming part of any suitable supporting structure which has not been otherwise shown. Beneath the table top there is mounted, in a conventional manner, an electric transmitter 12 comprising an electric motor 13 and a clutch which includes a driving member 14 secured to the motor shaft and a driven member 15 secured to an axially slideable shaft 16. A lever 17 pivotally carried by a lug 18 projecting from the frame of the motor and clutch unit is normally rocked in a clockwise direction (Figure I) by a spring 19 and serves to hold the shaft 16 toward the right, i. e., in a position in which the clutch is disengaged. When it is desired to operate the sewing machine the lever 17 may be rocked in a counterclockwise direction by suitable connections from a foot treadle or knee control member (not shown). A pulley 20 secured to the shaft 16 and driven by the latter whenever the clutch is engaged is connected by a belt 21 with a combined handwheel and pulley 22 secured to a main operating shaft 23 which constitutes the only rotary shaft in the sewing machine. For further details as to the construction, mounting, and operation of the electric transmitter reference may be had to the pending application of George Sauer, Serial No. 442,585, filed on May 12, 1942, now Patent Number 2,418,429 dated April 1, 1947.

Turning now to the construction of the sewing machine, this comprises a hollow frame which serves to support and substantially completely enclose the operating mechanism of the machine. This frame, as illustrated, is of the flat-bed type and includes a base portion 24 (Figures I and II), a vertical standard 25 rising from one end of the base, and a short overhanging arm 26 carrying a needle head 27 at its free end. The shaft 23 is supported at its right end (Figure II) by a bearing bushing 23a mounted in a housing 28 in the end wall of the vertical standard adjacent its top and is journaled adjacent its forward end in a partition 29 which serves to divide the main portion of the overhanging arm from the needle head. Within the needle head there is secured to the shaft 23 a balanced crank member 30 carrying a crank pin 31 which is connected by a pitman or link 32 with a block 33 secured to a needle bar 34. At its lower end the needle bar carries one or more needles 35 (two being shown) adapted to be reciprocated upon rotation of the shaft 23. The points of the needles are carried from a position some distance above the work supporting surface 36 of the base to and through a throat plate 37 mounted in the work support.

Beneath the throat plate there is provided a pair of loopers 38 adapted to cooperate with the needle thread loops formed as the needles start to rise from their lower-most positions. These loopers are carried by a rod 39 which is mounted for axial reciprocation in a rock frame 40 secured to a rock shaft 41. This shaft is mounted in suitable bearings 42 and 43 carried by integral portions of the base of the frame. Loop taking and loop shedding movements are imparted to the loopers by reciprocation of the rod 39, while needle-avoid movements are given to the loopers by the rocking of the frame 40. These movements are derived from the shaft 23 by suitable connections which will now be described. A crank portion 44 of the shaft 23 is connected by a pitman 45 with a ball formation adjacent the end of an arm 46 of a rock member secured to a shaft 47 journaled in the vertical standard 25.

5 A downwardly extending arm 48 of the rock member is connected by a pitman or link 49 with a ball ended stud 50 carried by the looper carrying rod 39. It will be seen that through these connections reciprocations will be imparted to the rod 39 as the shaft 23 is rotated.

An eccentric 51 carried by the shaft 23 (Figure II) cooperates with a strap 52 at the upper end of a link or pitman 53 which is connected at its lower end, by a ball and strap construction, with an arm 54 forming part of a rock member mounted on a shaft 55 (Figures III and V) suitably journaled in portions 56 and 57 of the frame. A downwardly extending arm 58 of the rock member is connected by a link 59 with a stud 60 projecting from the rock frame 40. Link 59 is connected with the arm 58 by means of a bolt or screw 61 cooperating with an arcuate slot 62 in the arm. This permits adjustment of the bolt 61 to any desired position within the slot 62 to vary the extent of the rocking movement imparted to the rock frame 40.

Another arm 63 forming part of the rock member mounted on the shaft 55 is connected by an extensible link 64 with an arm 65 secured to a hollow shaft 66 suitably journaled in the base of the machine frame. Arm 63 is provided with an elongated arcuate slot 67 cooperating with a bolt type ball stud 68 by which the link 64 is connected through a ball and strap with the arm, thereby permitting adjustment of this connection as desired. As will be presently explained, the rocking of the shaft 66, by the connections just described, serves to impart the feed and return movements to the feed dog. It will be apparent, therefore, that adjustment of the stud 68 within the slot 67 serves to vary the length of the stitch to be formed.

Referring now to Figures III and VI, there is secured to the shaft 66 a rocker 69 having two upwardly extending arms serving to pivotally support, at their upper ends, one end of a feed bar. This feed bar is preferably formed in two sections, 70 and 70a, connected together by a bar or rod-like extension 71 of the part 70a, this extension being of reduced diameter adapted to pass through an opening 72 in a wall 73 of the base of the frame. The overall length of the bar may be varied by adjusting the position of the member 70 in relation to extension 71. Set screws 71a serve to hold the parts in assembled relation. Opening 72 is slightly elongated in a vertical direction to permit the necessary lifting and lowering movements of the feed bar. Adjacent its forward end the feed bar carries a feed dog 74 which is adjustably secured to the forward member of the bar by means of a screw 75 cooperating with an elongated slot 76 in the feed dog. A downwardly and forwardly extending portion 77 of the feed bar has its forward end pivotally connected with a link 78 which, at its opposite end, is connected with an arm 79 secured to a shaft 80. Shaft 80, as best shown in Figures II and IV, is mounted in suitable bearings carried by the base of the frame, one of these bearings being mounted in a wall 81 of the frame forming part of the lubricant retaining housing and disposed at right angles to the wall 73. Within the enclosed portion of the frame there is secured to the shaft 80 an arm 82 which is connected at its free end by a link or pitman 83 with a strap 84 cooperating with an eccentric 85 secured to the shaft 23. It will be apparent that through the connections just described, lifting and lowering movements will be imparted to

the feed bar and the feed dog, while longitudinal movements, for feed and return strokes of the feed dog, will be given to the bar by the rocker 69 as the shaft 66 is rocked, through the connections described, by the eccentric 51.

Cooperating with the feed dog to advance the work over the work supporting surface is a presser foot 85, of any suitable construction, mounted upon the lower end of a presser bar 86 which is slidable vertically in the needle head. At its upper end the bar 86 carries a flanged, thimble-like member 86a which is engaged by the forked end of a leaf spring 87 (Figures II and VI) which extends substantially the full length of the overhanging arm 26 just beneath the top of the latter. The spring 87 extends through an opening in the wall 29 and at its opposite end is apertured to receive a retaining stud 88 carried by a boss 89 extending inwardly from the rear wall of the machine frame. Intermediate its ends the spring is engaged by a flange 90 formed on a screw 91 adjustably engaged with a lug 92 on the frame. It will be apparent that the tension of the spring 87 may be varied, as desired, by appropriate adjustment of the screw 91. For the purpose of lifting the presser bar, to enable free shifting of the work, an arm 93 secured to a hollow shaft 94 is provided. A spring 95 normally urges the arm 93 in a clockwise direction (Figure VI) to a position in which clearance is provided between the upper surface of the arm and the lower surface of a block 96 secured to the presser bar. Shaft 94 extends longitudinally of the overhanging arm 26 and is suitably journalled in the frame. Its innermost end is journalled in a lug 97 projecting inwardly from the rear wall of the arm at the top of the vertical standard. This lug has an opening 98 extending outwardly from the shaft to the outer rear surface of the frame. An arm 99 secured to the shaft extends through the opening 98 to the outside of the frame and constitutes the means for rocking the shaft at will. A chain or other suitable connection may be provided from the end of the arm to a foot treadle or knee-controlled member (not shown). It will be apparent that as the arm is depressed (Figure VI) and the shaft 94 is rocked counter-clockwise, arm 93 will engage the block 96 to lift the presser bar and the presser foot.

The interior of the frame, between the partition member 29 in the overhanging arm and the walls 73 and 81 in the base, constitutes a substantially oiltight and dusttight compartment for housing the various operating parts hereinbefore described. Provision is made for dispersing lubricant 100, which is held in a reservoir provided in the base, in the form of a mist of fine lubricant particles which are distributed throughout the hollow of the frame. The means for so dispersing the oil comprises a pair of plate-like members 101 and 102, best shown in Figures II, III, IV, V, and VII, which are secured to the hollow shaft 80. These members are long and flat and are oscillated through the oil upon the rocking of the shaft 80. They are each provided with a series of indentations 103 on each face, these indentations having the general contour indicated in Figure V and a cross-section such as indicated in Figure VII. Abrupt shoulders are provided at the straight bottom edges of the indentations but gradual slopes are provided at the tops and ends. Thus, the form of the indentations is such that as they are carried downwardly into the lubricant, upon the rapid oscil-

lation of the plates, they will have relatively slight splashing effect, but as they are carried upwardly they will pick up a small amount of oil and will throw it upwardly into the standard, thus creating the desired lubricant mist. The two plates may be of identical construction but preferably have the hubs or collars by which they are attached to the shaft 80 on opposite sides, as shown. They are preferably secured to the shaft by means of set screws 104 (see Figure IV).

It will be understood that the lubricant mist will be distributed over the various relatively sliding surfaces and effect thorough lubrication of the parts. In addition to reaching the surfaces of the various eccentrics and straps and the connections between the various pitmans or links and the rock members, or the like, a portion of the lubricant will be collected in a small pocket 105 provided adjacent the top of the frame (Figure II) from which it will be supplied through an opening 106 to the bearing surface which supports the shaft 23 in the end wall of the standard. Excess lubricant seeking to escape from this bearing will be returned through a duct 107 to the supply in the base. Some of the mist will be collected in an open pocket 108 formed in the top of the rock shaft 94 intermediate its ends. This lubricant will be delivered through the bore of the shaft into the needle head where it will accumulate in a small reservoir 109. Any excess lubricant so delivered will be returned to the main reservoir in the base through a duct 110 passing through the lower wall of the overhanging arm. Within the needle head the lubricant will be whipped into a spray by the scoop-like extension 32a at the lower end of the link 32. This scoop is carried into and through the lubricant in the reservoir 109 upon each cycle of the machine.

Lubricant may be introduced into the machine through a normally closed opening 111 in the needle head, or a similar opening 112 in the top of the overhanging arm in the region of the vertical standard. Various expedients may be adopted for facilitating the lubrication of the relatively sliding surfaces in the base. For example, the inner bearing 43 for the shaft 41 may be supplied with a portion of the dispersed lubricant which is collected and delivered through the opening 113 into the center of the bearing.

As best shown in Figures II, III, IV, and VI, the loopers and the feed dog are located outside of the lubricant retaining portion of the frame. This is to render these parts readily accessible and also to avoid the danger of throwing lubricant onto the work or the stitching threads. However, the means for operating the loopers and the feed dog are, as far as possible, placed within the enclosed portion of the housing. The shaft 80 which operates the feed dog lifting link 78 passes through a wall of the enclosure and the bearing surfaces of the link 78 are the only relatively sliding surfaces which are outside of the range of the lubricating mist. As previously indicated, a slightly enlarged opening 72 is provided for the passage of the feed bar 71 to enable the latter to be lifted and lowered in the manner required, as well as shifted longitudinally. A similarly enlarged opening 114, Figure VI, is provided to permit the horizontal or lateral movement of the looper carrying rod 39 as the latter is given its needle-avoid movements. A small amount of lubricant may escape through the openings 72 and 114 around the respective bars 75 but this is not sufficient to do any serious harm.

However, if it is desired to completely eliminate this leakage of the lubricant, a number of sealing washers 115 may be provided around the reduced connecting rod 11 of the feed bar and urged by a spring 116 against the wall 73. This arrangement is such that the washers do not interfere with the various movements imparted to the feed bar, but at the same time they provide an effective seal for the opening 72. A similar arrangement, including washers 117 and a spring 118 may be provided with respect to the looper carrying bar 39.

In lieu of the sealing arrangement above described, one or both of the bars 39 and 71 may be made square in cross-section and may be passed through slightly elongated openings in the respective walls to permit the necessary movements of the bar. This permits a slight reduction in the cross-sectional area of the openings through which the lubricant may escape. An arrangement of this character is illustrated in Figure VIII in which the feed bar 71b is shown as of square cross-section and the opening 72a is shown as of rectangular cross-section.

To provide access to the interior of the enclosed housing and particularly to enable adjustment of the connections 61 and 62, a large removable screw plug 119 is provided in the wall 84, as shown in Figures III and VI.

For the purpose of dissipating the heat generated within the hollow frame due to the high speed operation of the machine, means are provided for continuously withdrawing the heated air from the interior of the frame. This means comprises a suction blower 120 which may suitably be of substantially the same construction as the pressure blower disclosed in the pending application of George Sauer, hereinabove mentioned. It may comprise a housing 121 detachably secured by wing bolts 122 to a plate 123 which is adjustably connected with the frame of the transmitter unit by a series of bolts 124. A rotor member 125 of the blower may be secured to the hub of the pulley 20 or to the shaft 16. For further details as to this construction, reference may be had to said pending Sauer application. The blower housing, however, is of slightly different construction and is provided with a central opening having an outwardly projecting collar 126 adapted to receive a frustoconical connector 127 provided at the end of a conduit 128. This conduit is connected, through a coupling 129, with another conduit 130 which passes upwardly through an opening 131 in the table and which may be clamped in desired position by any suitable clamping means 132. The upper end of the conduit 130 is suitably connected with an outwardly projecting collar surrounding an opening 133 in the rear wall of the overhanging arm of the sewing machine frame. Through the conduits described the interior of the sewing machine frame will be subjected to suction or partial vacuum continuously during the operation of the machine. This suction action is transmitted to the needle head through the opening in the wall 29 through which spring 87 extends. To create an adequate suction action upon the frame the conduits 128 and 130 and the associated passages should be of reasonably large diameter, i.e., about $\frac{3}{4}$ ". Air will leak into the frame of the machine to replace the air withdrawn, around the various shafts and bars which pass through the walls of the frame. It will also enter in part through the passage 107. If desired, other openings may be specially provided in the walls of the frame to

admit air. One such opening, provided with a screened air filter unit, is indicated at 133a in Figure I. Such openings should be so located as to minimize the danger of escape of the lubricant mist. The maintenance of a slightly reduced pressure within the frame will aid in preventing the discharge of the lubricant mist through any openings other than the opening 133.

Any suitable thread handling and controlling devices may be employed in connection with both the needle threads and the looper threads. As shown in Figure VI, these devices may suitably include thread tensioning means 134 mounted on the front wall of the vertical standard. The take-up means for the needle threads may include an arm 135, shown only in part in Figure VI, which is secured to the needle bar and which projects through the front face of the needle head to engage and act upon the needle threads in a manner well known in the art. The looper threads may be subjected to the take-up action of a swingable arm 136 cooperating with a fixed guide 137 (Figure VI). Arm 136 is secured to the end of the shaft 47, as best shown in Figure V, and partakes of the rocking movements of the latter imparted by the crank 44 in the manner hereinabove explained.

It is believed that the operation of the machine will be fully understood from the foregoing detailed description of the various parts. It may be briefly summarized as follows: The work to be stitched is inserted between the presser foot and the throat plate by lifting the presser foot through the operation of the arm 99. As above indicated the machine is particularly intended for the formation of seams along the edges of work pieces. Accordingly, very little space is required between the needle bar and the vertical standard. This space need be sufficient only to provide freedom of movement for the hand of the operator in introducing the work beneath the presser foot, in the manner set forth, and the subsequent manipulation of the work.

The work piece having been properly introduced the machine is set into operation by rocking the control lever 17 which causes engagement of the clutch of the electric transmitter unit. This not only brings about operation of the sewing machine but also the rotor of the blower 120. Operation of the latter serves to withdraw the heated air from the interior of the sewing machine frame and permits a desirable influx of cooler air through clearance spaces and other passages provided through the frame. All of the functions of the sewing machine are performed by suitable driving connections from the single rotary shaft 23 extending longitudinally of the upper arm. Various eccentric means on this main drive shaft serve to perform a variety of functions, such as reciprocation of the needle bar 34 and of the looper carrying bar 39. Eccentric means also serve to impart needle-avoid movements to the looper carrying bar, by the rocking of the frame 40 in which the bar is slidably mounted, and to impart the longitudinal feed stroke movements to the feed bar 70, 70a, as well as the lifting and lowering movements of the forward end of the bar to produce the desired four-motion operation of the feed dog 74. For accomplishing the five separate movements of the stitch forming and work feeding devices mentioned above, only four separate eccentric means are provided on the shaft 23. Separately adjustable connections are provided from one of these to two devices operated by it. Lubrication of the

various operating parts of the machine is accomplished by the oscillation, at high speed, of a pair of plates 101 and 102 secured to the rock shaft 80 which imparts the lifting and lowering movements to the feed dog. These plates serve to disperse the lubricant, retained in the base of the hollow frame, as a fine mist throughout the interior of the frame. Some of this lubricant is delivered to the needle head wherein it is also whipped into a mist by the action of the scoop 32a at the lower end of the needle bar actuating link 32.

While an illustrative embodiment of the invention has been described in considerable detail, it will be understood that numerous changes may be made in the construction and arrangement of the various parts without departing from the general principles and scope of the invention.

1. In a sewing machine having a frame including a base having an enclosed portion, a hollow vertical standard communicating with said enclosed portion of the base, and an overhanging arm terminating in a needle head, a reciprocable needle bar in said needle head, a looper in an unenclosed portion of said base, an elongated slide member carrying said looper and extending from the enclosed to the unenclosed portion of the base, a rock frame within the enclosed portion of the base by which said member is slidably carried and shifted bodily in a direction transverse to its sliding movement, work feeding devices in said base, a rotary shaft mounted in said overhanging arm and extending from a point outside of said standard to a point within said needle head, connections from said shaft in said needle head for reciprocating said needle bar, eccentric means on said shaft in the region of said standard, and connections from said eccentric means located within said standard and the enclosed portion of the base for reciprocating said slide member, rocking said rock frame and operating said work feeding devices.

2. In a sewing machine having a frame including a base having an enclosed portion, a hollow vertical standard communicating with said enclosed portion of the base and an overhanging arm terminating in a needle head, a reciprocable needle bar in said needle head, a looper in an unenclosed portion of said base, an elongated slide member carrying said looper and extending from the enclosed to the unenclosed portion of the base, a rock frame within the enclosed portion of the base in which said member is slidable and by which it is carried bodily in a direction transverse to its sliding movement, work feeding devices in said base, a rotary shaft mounted in said overhanging arm and extending from a point outside of said standard to a point within said needle head, connections from said shaft in said needle head for reciprocating said needle bar, eccentric means on said shaft in the region of said standard, and connections from said eccentric means located within said standard and the enclosed portion of the base for reciprocating said slide member, rocking said rock frame and operating said work feeding devices, said last mentioned connections including a common member driven by a single eccentric for rocking said rock frame and operating said work feeding devices.

3. In a sewing machine having a hollow frame including a base with a flat work supporting surface, a vertical standard and an overhanging arm in open communication and providing an enclosed lubricant retaining housing, a needle head at the end of said arm, a rotary shaft extending

longitudinally of said arm, a reciprocable needle bar in said head, and complementary stitch forming devices and work feeding means in said base, the combination therewith of connections from said rotary shaft comprising a plurality of eccentrics thereon and a plurality of non-rotary members driven thereby for operating said needle bar, said devices and said means, said connections comprising an oscillatory member, said base having a lubricant reservoir formed therein extending beneath said work supporting surface to a point near said devices, plate like means carried by said oscillatory member and extending constantly below the lubricant level in said reservoir for distributing lubricant as a mist throughout said hollow frame, means for delivering a portion of said distributed lubricant to said needle head, and means in said needle head for dispersing said lubricant throughout said head.

20 4. In a sewing machine having a hollow frame including a base with a flat work supporting surface, a vertical standard and an overhanging arm in open communication and providing an enclosed lubricant retaining housing, a needle head at the end of said arm, a rotary shaft extending longitudinally of said arm, a reciprocable needle bar in said head, and complementary stitch forming devices and work feeding means in said base, the combination therewith of connections from said rotary shaft comprising a plurality of non-rotary members driven thereby for operating said needle bar, said devices and said means, said base having a lubricant reservoir formed therein extending beneath said work supporting surface to a point near said devices, and rockable plate-like means associated with and driven by at least one of said non-rotary members of said connections for distributing lubricant as a mist throughout said hollow frame, said plate-like means having a portion extending constantly below the lubricant level in said reservoir.

5. In a sewing machine having a hollow frame including a base with a flat work supporting surface, a vertical standard and an overhanging arm in open communication and providing an enclosed lubricant retaining housing, a needle head at the end of said arm, a rotary shaft extending longitudinally of said arm, a reciprocable needle bar in said head, and complementary stitch forming devices and work feeding means in said base, the combination therewith of connections from said rotary shaft comprising a plurality of non-rotary members driven thereby for operating said needle bar, said devices and said means, said base having a lubricant reservoir formed therein extending beneath said work supporting surface to a point near said devices, and rockable plate-like means associated with and driven by at least one of said non-rotary members of said connections for distributing lubricant as a mist throughout said hollow frame, said plate-like means having formations in the surfaces thereof presenting only upwardly-facing abrupt shoulders and having a portion extending constantly below the lubricant level in said reservoir.

6. In a sewing machine having a hollow frame including a base, a vertical standard and an overhanging arm in open communication, a needle head at the end of said arm having an enclosed chamber in communication with the hollow of said frame, a rotary shaft extending longitudinally of said arm, a reciprocable needle bar in said head, complementary stitch forming devices and work feeding means in said base, and connections from said rotary shaft for operating said needle bar, said

devices and said means, said base having a lubricant reservoir formed therein, the combination therewith of means associated with said connections for distributing lubricant as a mist throughout said hollow frame and said needle head, power means for driving said shaft, and a suction blower driven by said power means and connected with said hollow frame at a relatively high point for withdrawing air therefrom whenever said machine is in operation without withdrawing any substantial amount of the lubricant.

7. In a sewing machine having a hollow frame including a base, a vertical standard and an overhanging arm in open communication, a needle head at the end of said arm, a rotary shaft extending longitudinally of said arm, a reciprocable needle bar in said head, complementary stitch forming devices and work feeding means in said base, connections from said rotary shaft for operating said needle bar, said devices and said means, and a motor and clutch unit connected for driving said shaft, the combination therewith of a suction blower arranged to be driven by said unit, and a conduit connecting said blower with said overhanging arm for withdrawing air from said hollow frame continuously during operation of the machine.

8. In a sewing machine having a hollow frame including a base, a vertical standard and an overhanging arm in open communication, a needle head at the end of said arm, a rotary shaft extending longitudinally of said arm, a reciprocable needle bar in said head, complementary stitch forming devices and work feeding means in said base, connections from said rotary shaft for operating said needle bar, said devices and said means, and a motor and clutch unit connected for driving said shaft, the combination therewith of a suction blower arranged to be driven by said unit, and a conduit connecting said blower with a side wall of said overhanging arm for withdrawing air from said hollow frame continuously during operation of the machine, said conduit being of relatively large diameter throughout.

9. In a sewing machine having a hollow frame including a base, a vertical standard and an overhanging arm terminating in a needle head, said base having a portion fully enclosed and having a

wall at the end of the enclosed portion, a reciprocable needle bar in said needle head, and a looper in said base, the combination therewith of an elongated slide member extending through said wall and carrying said looper at its outer end, a rock frame in which said member is slidable and by which it is shifted bodily in a direction transverse to its sliding movement, work feeding devices in said base, a rotary shaft mounted in said overhanging arm and extending from a point outside of said standard to a point within said needle head, connections from said shaft in said needle head for reciprocating said needle bar, eccentric means on said shaft in the region of said standard, connections from said eccentric means within said hollow frame for reciprocating said slide member, rocking said rock frame and operating said work feeding devices, said last mentioned connections including a rockshaft connected with said slide member, and looper thread take-up means mounted on said rock shaft exteriorly of said hollow frame for oscillation thereby.

NORMAN V. CHRISTENSEN.
